UNITED STATES PATENT OFFICE.

THOMAS H. JACKSON, OF PHILADELPHIA, PENNSYLVANIA.

WINDOW-SASH FASTENER.

Application filed May 26, 1921. Serial No. 472,700.

To all whom it may concern:

Be it known that I, THOMAS H. JACKSON, a citizen of the United States, residing at Philadelphia, in the county of Philadelphia and State of Pennsylvania, have invented 5 certain new and useful Improvements in Window-Sash Fasteners, of which the following is a specification.

One object of my invention is to provide 10 an improved fastener which can be quickly and easily attached to the sashes of a window and which will effectively lock the same and prevent the easy prying of the locked sashes.

Another object is to so construct my improved fastener that the major portion thereof can be directly secured to the upper edge surfaces of the lower sash by ordinary wood screws and if an attempt is made to pry or 20 "jimmy" the sash, the arrangement of the parts will prevent the screws from entirely pulling out of the sash.

Another object is to make my improved fastener of a strong and durable construction.

These objects, and other advantageous ends which will be described hereinafter, I attain in the following manner, reference being had to the accompanying drawings in 30 which—

Figure 1 is a fragmentary perspective view, partly in section, showing my improved fastener in position locking two sashes together,

Figure 2 is a fragmentary sectional plan view showing my improved fastener in an unlocked position,

Figure 3 is a sectional elevation taken centrally through a portion of my improved fastener and the sash to which it is connected and showing the same in an unlocked position,

Figure 4 is an inverted plan view of the portion of the fastener shown in Figure 3; the pivot being illustrated in section, and

Figure 5 is a sectional elevation showing how the parts of my improved fastener can act when an attempt is made either to pry the lower sash upwardly or the upper sash 50 downwardly.

Referring to the drawings, 6 represents the lower sash and 7 represents the upper sash of a window.

My improved device includes a base 8 which may be made of cast metal which has a front flange 9 which is preferably made

straight; the same forming one wall of a recess 10 extending upwardly from the bottom of the base. The flange 9 is continued rearwardly as shown at 11. The base has 60 a hollow upwardly extending portion 12 which provides a boss on its top surface; said boss being positioned inwardly from the outer part of the flange portion 11 to provide a ledge 13. The flange 9 is continued upwardly so as to form a closure for the front of the boss 12 as clearly shown in Figure 3. The boss 12 has a downwardly extending hole 14 in which rotatably fits the trunnion 15 of a latch 16. A pivot pin 17 70 extends through the latch and through a washer or ring 18 which is adapted to engage the lower surfaces of downwardly extending ribs 19 of said boss. The lower end of the pin 17 is preferably riveted over the 75 washer 18; said washer being of greater diameter than the hole 14 so that the latch is pivotally secured to the base. The trunnion 15 has flat portions 20 arranged at right angles to each other for engagement with a 80 strip spring 21 which has its ends bearing upon internal shoulders 22 of the boss as shown in Figure 4; it being noted that for the boss to turn, it is necessary for the angular junction of the flat surfaces 20 85 to engage and flex the spring 21 so that the latch can be swung in opposite directions to alternately present its flat surfaces in alignment with the spring so that the latch will not accidentally move out of the position 90 into which it is turned.

To facilitate the movement of the latch, I provide it with a handle extension 23. The latch 16 at a position opposite the handle has a tongue 24 which slants upwardly 95 from its end 25 in an arcuate path on its upper surface and said upper surface at the part 26 is made parallel with the bottom of the latch for a purpose hereinafter described. In other words, the tongue is only 100 beveled at a position adjacent the end 25 but at a position such as shown at 26, the tongue at its top surface is parallel with the bottom surface. The ledge 13 has screw holes 27 which extend downwardly so that 105 screws 28 can be inserted therethrough and screwed downwardly into the top of the bottom sash 6, as shown in Figures 1 and 3.

It will be noted that certain of these holes 27 are positioned close to the flange 9 110 of the base 8 and that another of the holes which is number 29 is positioned adjacent

the rear of the frame. A keeper plate 30 is adapted to be screwed to the upright surface 31 of the top sash 7 and this keeper plate, if the sash are close fitting, may be inserted within the portion 31 of the top sash, as shown in Figures 1 and 5. The keeper plate has a slot 32 which registers with a cavity 33 extending horizontally into the sash 7. The keeper plate and cavity 33 are so positioned that when the latch 16 is swung on its pivot the tongue 24 will pass through the slot 32 into the cavity 33 until the portion 26 passes under the upper wall of the slot 32 with the flange 9 of the base 8 positioned parallel with and directly in front of the outer surface of the keeper plate 30.

Considering that the parts are in their locked position as shown in Figure 1, if it is attempted to pry or "jimmy" the lower sash upwardly or the upper sash downwardly, the resulting action will cause the base to tilt on the lower edge of the flange 9 as a fulcrum and the screw 28 passing through the hole 29 will be pulled lengthwise partway out of the bottom sash. This tilting action will continue until the front surface 34 of the flange 9 engages the outer surface of the keeper plate and the parts will then jam so as to prevent further withdrawal of the screw which passes through the hole 29 in the boss. The other screws 28 will then receive a shearing action but in view of the fact that this action is transverse or in the direction of the thickness of the screws, it will be practically impossible for these latter mentioned screws to be broken or pulled out of the wood of the sash 6. By having the portion 26 of the upper surface of the tongue parallel with the bottom surface of the tongue, the lifting action of the lower sash or the lowering action of the top sash will not cause the latch to swing on its pivot and therefore the parts cannot be accidentally detached.

While I have described my invention as taking a particular form, it will be understood that the various parts of my invention may be changed without departing from the spirit thereof, and hence I do not limit myself to the precise construction set forth, but consider that I am at liberty to make

such changes and alterations as fairly come within the scope of the appended claims.

Having thus described my invention, what I claim as new and desire to secure by Letters Patent is:—

1. A fastener including a base adapted to be mounted on the upper surface of the lower window sash by means of upright screws, said fastener having a front flange with a straight upright surface, a latch with a trunnion movably secured to said base and having a locking tongue, spring means to engage said trunnion and hold said latch in positions and a keeper mounted on the upright surface of the upper sash and having a slot for the reception of the tongue of said latch, said keeper including an upright surface substantially parallel and in engagement with the upright surface of said base flange to engage the same and stop tilting of said base on the lower sash and preventing withdrawal of the screws in said base.

2. A fastener including a base provided with screws for mounting it on the upper surface of the lower sash, said fastener having a flat flange with a straight upright surface, a latch with a trunnion rotatably secured in said base and having an arcuate locking tongue with a bevelled portion, a spring to engage a flat portion on said trunnion and hold said latch in locking position and a keeper embedded in the upright surface of the upper sash and having a slot for the reception of said tongue, said keeper including an upright surface parallel with and in engagement with the upright surface of said base flange to engage the same and prevent excessive tilting of said base on said lower sash and to prevent said screws from pulling out longitudinally from said lower sash or the removal of said base therefrom upon movement of the sash when the latch is in locked position.

In testimony whereof I have signed my name to this specification in the presence of two subscribing witnesses.

THOMAS H. JACKSON.
